UNITED STATES PATENT OFFICE.

CHARLES WILLIAM DUNNING, OF LOS ANGELES, CALIFORNIA.

HORSESHOE-PAD.

1,169,324.

Specification of Letters Patent. Patented Jan. 25, 1916.

Application filed June 28, 1915. Serial No. 33,368.

To all whom it may concern:

Be it known that I, CHARLES WILLIAM DUNNING, a citizen of the United States, residing at Los Angeles, in the county of Los Angeles and State of California, have invented a new and useful Improvement in Horseshoe-Pads, of which the following is a specification.

My invention relates to horse shoe pads capable of being secured on the hoofs of horses conjointly with the metallic shoes and permanently held thereon by common means.

The primary object of my invention is to provide an anti-slipping pad especially adapted to cushion the feet against impact and jar and integrally formed of a good quality of rubber which may be conveniently and easily placed in position on the hoof between the horse shoe and the hoof.

20 A further object consists in the provision of means whereby sufficient suction may be created in the center of the pad beneath the frog of the foot so as to prevent the slipping thereof on wet or smooth pavements.

25 I am aware that Letters Patent of the United States have been granted upon devices for this same purpose, reference being had particularly to the Patent No. 503,849 to one Hallanan, dated Aug. 22, 1893, but I 30 am not aware that a pad embodying the particularly valuable features hereinafter disclosed has ever been before used or known.

With reference to the drawings, in which similar characters of reference indicate the 35 same parts throughout the several views, Figure 1 is an elevation of my pad shown in position on the hoof in connection with the ordinary type of metallic shoe. Fig. 2 is a bottom plan of the same with the metallic 40 shoe partly broken away. Fig. 3 is a longitudinal section of Fig. 2 on the line 3—3. Fig. 4 is a transverse section of the same on the line 4—4.

The particular form of pad disclosed in 45 the Letters Patent hereinbefore described, consists of a central cushion member to which is secured a flat flanged member of leather, the latter member being interposed between the hoof and the metallic shoe. In 50 my pad, which conforms to the shape of the foot, the entire structure is integral and formed of a yieldable grade of rubber so that all portions of the foot are equally protected against impact and jar. The flat flange 1 is adapted to receive the metallic 55 shoe 2, is on the upper side of the pad in di-

rect contact with the hoof 3, and is substantially thicker at the heel than at the front for the purpose of providing additional resiliency at the points of greatest impact, this 60 being a valuable improvement in such devices and the difference in thickness gradually increasing in the direction of the heel.

In the center of the pad beneath the frog of the foot a pocket 4 is formed which has 65 a bottom of relatively thinner cross section than the flange 1, for the purpose of providing sufficient elasticity beneath the sensitive portion of the foot, and also of serving to create a slight suction in the pocket when 70 the foot is placed on the pavement. This feature, in addition to forming a cushion for the sensitive portion of the foot, also assists in rendering the pad anti-slipping in character. The walls of the pocket 4 form a 75 bead 5 which depends from the flange 1 when the pad is in position on the foot, and the bottom side of the bead is serrated to prevent its slipping.

The shoe is placed on the pad with the 80 bottom thereof substantially lower than that of the bead 5, the heel portion being lower than the front, and the nails 6 which hold the shoe in place also serve to hold the pad firmly on the foot. The bead 5 fits snugly 85 into the horse shoe and in contact with the inner curved side thereof, thus preventing a movement of the pad on the foot in the event that the holes through which the nails are inserted should become worn or enlarged. A backing of heavy canvas 7 is 90 suitably formed on and integral with the upper face of the flange 1 and extends over the entire area of the upper portion of the pad, thus serving to hold the rubber firmly 95 against breakage or cracking, due to excessive wear, strain or conditions of the weather.

Having thus described my invention, what I claim as new and desire Letters Patent 100 for, is:—

1. A pad for horse shoes integrally formed of rubber with a flat flanged portion extending over the entire area of the foot and gradually increasing in thickness from the front 105 to the heel, a depending bead arranged beneath the frog of the foot and fitting the inner curve of the horse shoe, and a relatively thin and highly resilient inner flat portion forming a cushion for the frog of 110 the foot.

2. A pad for horse shoes consisting of an

integral flanged and beaded member adapted to be interposed between the foot and the horse shoe and secured to the foot, said flange being substantially thicker at the 5 front than and tapered toward the heel and provided with a heavy canvas backing, said bead extending downwardly from said flange to a point substantially lower than the shoe and forming a pocket therewithin, 10 and the bottom of said pocket being relatively thinner than said flange and resilient for cushioning the sensitive portions of the foot and for preventing the slipping of the pad, as set forth.

15 3. A pad for horse shoes consisting of an integral flange and bead reinforced by a

heavy canvas backing for preventing the breaking thereof and formed of rubber, said flange being of varying thickness at different points for providing additional resiliency beneath the points of greatest impact, 20 said bead extending downwardly therefrom to a point substantially lower than the shoe and forming a pocket therewithin, and the bottom of said pocket being relatively thinner than said flange for providing a maximum resiliency beneath the frog of the foot. 25

CHARLES WILLIAM DUNNING.
